[57] **CLAIM**

The ornamental design for a pole level, as shown and described.

DESCRIPTION

FIG. 1 is a top, front perspective view of a pole level showing our new design, the broken-line showing of a pole being environmental and forming no part of the claimed design;

FIG. 2 is a top plan view thereof;

FIG. 3 is a right side perspective view thereof.

FIG. 3

FIG. 2

FIG. 1
